UNITED STATES PATENT OFFICE

SALOMON ROBERT MIRMAN, OF ST. LEU-LA-FORET, FRANCE

MANICURE SET FOR LADIES' HAND BAGS

Application filed December 22, 1930, Serial No. 504,097, and in France February 4, 1930.

This invention has for its object a manicure set adapted to be placed in a lady's hand bag and is essentially characterized by the fact that the polisher is made in the shape of a box which is closed by a cover and is adapted to enclose the various tools as well as the creams or pastes used by manicures for treating the hands.

According to the present invention, the manicure set is constituted by two hollow bodies one of which is externally lined with a skin serving to polish the nails and is provided, on the inner face of its bottom, with two small cups, closed by a cover, adapted to contain the creams or pastes usually employed for colouring and polishing the nails, and to hold in place a pair of scissors in open position.

The second hollow body is connected to the first one by a hinged joint and constitutes the cover of the manicure set. It is internally provided with spring clips secured on its bottom and adapted to hold in position, in the said cover, a number of manicure tools which are placed, at one of their ends, above a spring blade so arranged as to tend to push back the tools located above it upon opening of the clip which embraces them for lifting them and thus allowing to easily remove them.

In its preferred embodiment, the manicure set forming the subject-matter of the invention, is provided with a metal cup or cap which fits on the manicure set and covers the skin, in order to ensure the protection of the latter when the manicure set is not in use.

Moreover, the pair of scissors of the manicure set is so devised as to allow to bring the blades in such an open position that the rings may be fitted over the cups containing the creams or pastes and that the scissors be held in position in the manicure set by the said cups.

In order that the invention may be clearly understood, a form of construction of the manicure set according to the invention will be described hereinafter with reference to the accompanying drawings, in which:

Fig. 1 is a front elevation of the manicure set in closed position.

Fig. 2 is a corresponding plan view.

Figs. 3 and 4 are vertical sections made respectively according to lines 3—3 and 4—4 of Fig. 2.

Fig. 5 is a plan view of the manicure set in open position.

Figs. 6 and 7 are two vertical sections made respectively according to lines 6—6 and 7—7 of Fig. 5.

Fig. 8 shows in front elevation the pair of scissors of the manicure set in closed position.

Fig. 9 shows the same pair of scissors in completely open position for placing it in position in the manicure set.

As illustrated in the accompanying drawings, the manicure set forming the subject-matter of the invention is essentially constituted by a box 1, made of metal or other suitable material and closed by a metal cover 2 provided with a covering of suitable material with a handle 3 and connected, by a hinge 4, to the box 1.

On the box 1 is secured a skin 5 for polishing the nails, and a cap 6, made of metal or other material, and so arranged as to tightly fit on the box 1 for entirely covering the skin 5 and protecting it when the manicure set is not in use.

The box 1 is internally provided with two cups 7 and 8 secured on its bottom and each closed by a cover 9—10; these cups 7 and 8 are adapted to contain the creams or pastes used by manicures for treating the nails.

The box body thus devised serves as a housing for a pair of scissors, the two curved blades 11 of which, pivoted one on the other at 12 and terminated by rings 13 in the known manner, are each cut away at 11°, as shown in Fig. 8, so as to bring the said blades, as illustrated in Fig. 9, in such an open position that both rings 13 may be fitted over the cups 7 and 8 of the manicure set and that the pair of scissors, in this open position, be housed in the box 1 and held in place in the latter by the said cups 7 and 8.

The cover serves to receive the various tools used by manicures and, for that purpose, it is provided with spring clips 14 equal in number to that of the tools to be

placed in the cover, and each so arranged as to resiliently embrace and hold other manicure tools in position in the said cover, and means in this cover for facilitating the removal of the tools it contains.

In the example illustrated, these tools, five in number, are respectively a nail-scraper 15, a flesh-pusher 16, a file 17, a nail-cleaner 18 and a corn-cutter 19. They are each constituted by a suitably shaped steel blade secured in a flat handle 20 terminated at its free end, by a tapered portion serving as flesh-pusher, as clearly shown in Fig. 5.

The under surface of the cover 2 is fitted with a leaf spring 21 above each of the operative ends of the tools, such spring acting normally to hold the tool against the clips 14.

By means of this arrangement, the polisher being open as shown in Fig. 5, if two pairs of the clips 14 are opened by hand, the corresponding tools pushed back by the spring blade 21 are lifted slightly to be positioned between the outer ends of the clips and emerge above the others so as that it can be conveniently grasped and easily removed from the manicure set. In the same open position of the polisher, the pair of scissors can obviously be removed from the manicure set and replaced after use without any difficulty.

The above described arrangements are, of course, given by way of example only; the forms, materials and dimensions of the constituent parts, as well as the constructional details can be modified without departing thereby from the scope of the invention.

I claim:—

1. A manicure set adapted to be placed in a lady's hand bag, comprising a box body, a skin for polishing the nails, fitted on this box body, a removable cap adapted to cover and protect the skin, a hollow cover for closing the said box and constituting with the latter the polisher of the manicure set, two cups secured on the bottom of the box body and adapted to contain pastes for treating the nails and for holding nail scissors in open position in the said box body, a lid closing each of the said cups, means for securing and holding in position other manicure tools in the cover, and means for facilitating the removal of these tools.

2. A manicure set adapted to be placed in a lady's hand bag, comprising a box body, a skin for polishing the nails, fitted on this box body, a removable cap adapted to cover and protect the skin, a hollow cover adapted to close the said box and to constitute with the latter the polisher of the manicure set, a handle on this cover for handling the polisher, two cups secured on the bottom of the box body and adapted to contain pastes for treating the nails and to hold nail scissors in position in the said box body, a lid closing each of the said cups, spring clips secured on the bottom of the cover and adapt-

ed to resiliently embrace and hold other manicure tools in position in the said cover, and means in this cover for facilitating the removal of the tools it contains.

3. A manicure set adapted to be placed in a lady's hand bag, comprising a box body, a skin for polishing the nails, fitted on this box body, a removable cap adapted to cover and protect the skin, a hollow cover adapted to close the said box and to constitute with the latter the polisher of the manicure set, a handle on this cover for handling the polisher, two cups secured on the bottom of the box body and adapted to contain pastes for treating the nails and to hold nail scissors in position in the said box body, a lid closing each of the said cups, spring clips secured on the bottom of the cover and adapted to resiliently embrace and hold other manicure tools in position in the said cover, a spring blade secured on the bottom of the cover and adapted to determine, after opening of one of the spring clips, the lifting of one of the ends of the tool corresponding to the said clip and the presentation of this tool in suitable position for its removal.

The foregoing specification of my manicure set for ladies' hand bags, signed by me this 2nd day of December, 1930.
